MEANS FOR USE IN MANUFACTURING
MOCCASINS

René E. Duplessis, Beverly, Mass., assignor to
United Shoe Machinery Corporation, Patri-
son, N. J., a corporation of New Jersey

Original application February 18, 1935, Serial No.
6,931. Divided and this application February
20, 1936, Serial No. 64,911

11 Claims. (Cl. 12—107)

This invention relates to means for use in the manufacture of moccasins for holding in lasted position the forepart of a moccasin bottom, the moccasin bottom being that portion of the moccasin which provides an integral covering for the bottom of the forepart of the foot and extends upwardly and inwardly over the top of the forepart of the foot. This application is a division of my copending application Serial No. 6,931, filed February 18, 1935.

It is an object of the present invention to provide means portable with the moccasin and its last for clamping the forepart of the moccasin bottom in lasted position and holding it while it sets to the last or, alternatively, while a toe piece is secured to the margin of the moccasin bottom. It is a further object of the invention to provide means for holding the moccasin bottom in lasted position in order to permit the margin of its forepart to be trimmed for the reception of a toe piece. Accordingly, a feature of the invention consists of a clamp for holding the forepart of a lasted moccasin bottom against a last, said clamp comprising a device constructed and arranged to engage the bottom, the upstanding portion, and the overlasted margin of the lasted moccasin. The clamping device, in the illustrated embodiment of the invention, is held against the moccasin by a heel-engaging member connected thereto and movable heightwise of the lasted moccasin to engage its heel end thereby to force the moccasin forwardly thereof into the clamp. Said clamp, in accordance with a further feature of the invention, has associated therewith a forepart trimming gage whereby the overlasted margin of the forepart of the moccasin bottom may be trimmed along a line predetermined with relation to the last.

The invention will now be described with reference to the accompanying drawing and pointed out in the appended claims.

In the drawing,

Fig. 1 is a perspective view of a clamping device embodying the features of the present invention;

Fig. 2 is a detail perspective view of a guard plate for protecting the last during the trimming operation, said plate being shown in position on the forepart of a last;

Fig. 3 is a plan view of a moccasin bottom held in lasted position on its last by the clamping device illustrated in Fig. 1 and a cutter engaged in trimming the overlasted margin of the moccasin bottom, the central portion of the moccasin and last and the clamping device being broken away; and

Fig. 4 is a detail plan view of the forepart of a moccasin and last with the clamp illustrated in Fig. 1 mounted thereon, the forepart of the moccasin having been trimmed and the trimming gage retracted and a toe piece partially stitched to the margin of the forepart, the rear portion of the clamp being broken away.

In manufacturing moccasins with the aid of the illustrated clamping means, the forepart of a moccasin bottom is lasted in a machine such, for example, as the moccasin lasting machine disclosed in my copending application above referred to, and while the moccasin bottom is held in lasted position by the toe-embracing lasting members of the machine the margin of the moccasin bottom which has been lasted over the top of the forepart of the last is temporarily secured to the last, for example, by means of a toe-binding wire the function of which is merely to hold the moccasin bottom in lasted position during the interval between the removal of the lasted moccasin from the lasting machine and the application of the illustrated clamping device thereto.

The illustrated clamping device is constructed and arranged to engage the bottom and side faces of the forepart of a moccasin bottom 10 on a last 12 and has a clamping arm pivoted thereto and arranged to press the lasted moccasin forwardly thereof into said clamping device. The clamping device comprises a base plate 14 (Fig. 30 1) and a plate 16 which has the general shape of the peripheral face of the forepart of the last and is cut away as indicated at 18 and 20 to promote resiliency and to reduce the weight of said plate. The plate 16 is secured to the base plate 14 by clamping screws 22 arranged to extend through slots 24 in inturned ends 26 of legs 28 extending from the plate 16, said inturned ends 26, as illustrated in Fig. 1, extending beneath the margin of the base plate 14. Thus it will be seen that the plate 16 may be adjusted to accommodate different sizes of moccasins. Mounted on the plate 16 is a gage plate 30 which, as illustrated in Fig. 3, defines a line along which the margin of the moccasin bottom is cut in order to sever the excess margin 32 from the body portion of the moccasin bottom and to provide a suitable edge face for the reception of the edge face of a toe piece 34 (Fig. 4). The gage plate 30 is mounted on brackets 36 (Fig. 1) extending forwardly from the forward end of the plate 16 and similar brackets 38 extending outwardly from opposite sides of said plate, the gage plate 30 being provided with ears 40 constructed and arranged to register with said brackets. The

gage plate 30 is held on said brackets by headed pins 42 extending upwardly from said brackets, rolls 44 being pivoted on said pins for engagement within suitable slots 46 in the ears 40. The 5 slots 46 adjacent to the toe end of the moccasin extend substantially lengthwise of the moccasin (Fig. 3) while the slots 46 adjacent to the sides of the moccasin diverge forwardly of the moccasin. The plate 30 has a narrow portion 48 at 10 its toe end and similar narrow portions 50 between its ears 40 at opposite sides of the plate, said narrow portions being sufficiently resilient to permit movement of the plate 30 from its operative position, as illustrated in Fig. 3, to its 15 retracted position, as illustrated in Fig. 4. In order to retain the gage plate 30 in its retracted position, the diverging slots 46 at their rearward ends are provided with outward extensions 52 (Fig. 3) within which the rolls 44 are seated 20 when the gage plate 30 is in its retracted position, engagement of said rolls in said extensions being effected by the spring of the plate 30 which tends to return it to its operative position. After 25 retracting the gage plate 30 the toe piece 34 may be stitched to the upstanding margin of the forepart of the moccasin bottom 10, part of the stitching being illustrated at 58 in Fig. 4. It will be noted that the edge face 54 of the plate 16, as illustrated in Fig. 4, is parallel to the edge 30 face 56 of the trimmed vamp and spaced therefrom sufficiently to afford the necessary clearance for the stitch-forming instrumentalities but nevertheless close enough to the edge face 56 to 35 serve as a gage for the formation of the outside line of the hand-sewn seam 58.

In order to press that margin of the plate 16 adjacent to its edge face 54 downwardly against the overlasted moccasin bottom 10 a resilient plate 60 (Fig. 1) is secured to the base plate 14 40 for engagement with the moccasin bottom 10, a central opening being provided in the base plate for the reception of the plate 60. As herein illustrated, the end portions of the resilient plate are passed under and around the end portions of 45 the base plate 14 and secured to the upper surface of said base plate, for example by rivets 62. The central portion 64 of the resilient plate is normally positioned above the plane of the base plate 14 and provides a flat, resilient support 50 which is depressed somewhat in forcing the toe clamp over the moccasin bottom 10. The pressure of the resilient plate 60 against the moccasin bottom 10 is sufficient to hold the margin of the plate 16 firmly against the overlasted margin 55 of the moccasin bottom and said plate also maintains a firm contact of the gage plate 30 with the overlasted margin of the moccasin bottom during the trimming operation above described.

The plate 16 is drawn rearwardly of the moccasin and pressed firmly thereagainst by the 60 operation of a swinging U-shaped member 66 pivoted to upstanding lugs 68 formed in the base plate 14 at opposite sides thereof, the crossbar 70 65 at the rearward end of the member 66 having secured to its forward face a resilient plate 72 which is curved forwardly and upwardly of the moccasin for engagement with its heel end. The operative position of the plate 72 relatively to the 70 moccasin is determined by a U-shaped crossbar 14, the uprights of which are secured at their upper extremities to opposite sides of the U-shaped member 66 thereby positioning the horizontal portion of the crossbar 74 for engagement 75 with the bottom face of the heel end of the moccasin

in order to locate the plate 72 in operative relation to the moccasin.

While the manufacture of moccasins in accordance with the present invention has been described in connection with the description of the 5 illustrated clamping device, a further description of one method of manufacturing moccasins with the aid of the illustrated clamping device may serve to promote a better understanding of the invention. The moccasin bottom 10 having been 10 lasted and secured in lasted position, for example by means of a toe-binding wire as above described, the lasted moccasin bottom is positioned in the clamp illustrated in Fig. 1 and the excess margin 32 of the moccasin bottom is trimmed off. 15 If desired, a guard plate, for example the plate 76 illustrated in Fig. 2, may be positioned on the last 12 to prevent the trimming cutter 78 from injuring the last. After trimming the moccasin bottom the gage plate 30 is retracted and the 20 guard plate 76 is removed from the last. Cement is then applied to the edge face of the overlasted 25 margin of the moccasin bottom and to the corresponding edge face of the toe piece 34 and said edge faces are brought together, the position of the toe piece 34 on the last being determined by the registration of suitable notches in the moccasin bottom and the toe piece, respectively. After the cement has set, the moccasin bottom 30 and toe piece are permanently united, for example by a hand-sewn seam 58, whereupon the clamp is removed from the work.

Having thus described my invention, what I claim as new and desire to secure by Letters Patent of the United States is:

1. A clamp for holding a lasted moccasin bottom against a last comprising a device constructed and arranged to engage the bottom, the upstanding portion, and the overlasted margin of the lasted moccasin.

2. A clamp for holding the forepart of a lasted moccasin bottom against a last comprising a device constructed and arranged to engage the bottom and the upstanding portion of the forepart of the lasted moccasin, and resilient means for urging said member heightwise of the lasted moccasin thereby to press the marginal portion of said device against the overlasted margin of the moccasin bottom.

3. A clamp for holding the forepart of a lasted moccasin bottom against a last comprising a resilient member having the general shape of the forepart of the last, a member constructed and arranged to engage the heel end of the last and force the last forwardly thereof against said forepart-engaging member, and means connecting said members.

4. A clamp for holding the forepart of a moccasin bottom against a last comprising a member having the general shape of the forepart of the last, a member constructed and arranged to engage the heel end of the last and force the last forwardly thereof against said forepart-embracing member, and means connecting said members constructed and arranged to permit movement of the heel-engaging member heightwise of the last.

5. A clamp for holding the forepart of a moccasin bottom against a last comprising a member having the general shape of the forepart of the last, a member constructed and arranged to engage the heel end of the last and force the last forwardly thereof against said forepart-engaging member, means connecting said members constructed and arranged to permit movement of the 70 75 80 85 90 95 100 105 110 heel-engaging member heightwise of the last, and a gage associated with said connecting means for determining the operative position of said heel-engaging member heightwise of the last.

- 5 6. A clamp for holding the upstanding margin of the forepart of a moccasin bottom against a last comprising a member having the general shape of the forepart of the last, a U-shaped member the ends of which are pivoted to the 10 forepart-engaging member at opposite sides thereof, and a presser member secured to the crossbar of said U-shaped member, the arrangement of said U-shaped member and said presser member being such that movement of the U-shaped member to bring its crossbar into alignment 15 with the last brings said presser member into engagement with the heel end of the last and causes said presser member to press the last forwardly thereof against said forepart-engaging member.

7. A clamp for holding the forepart of a moccasin bottom against a last comprising a base member, a last-embracing member secured to said base member, said last-embracing member having the general shape of the forepart of the last, and pressing means mounted in said base member and arranged to apply pressure to the last bottom thereby to clamp said forepart-engaging member against the overlasted portion of the 25 forepart of the moccasin bottom.

8. A clamp for holding the forepart of a moccasin bottom against a last comprising a member having the general shape of the forepart of the last, a base member to which the forepart-engag-

ing member is secured, a forepart-trimming gage mounted on said forepart-engaging member, and pressing means mounted in said base member and constructed and arranged to apply pressure to the last bottom thereby to press said gage 5 against the overlasted portion of the forepart of the moccasin bottom.

9. A clamp for holding the forepart of a moccasin bottom against the last comprising a member having the general shape of the forepart of 10 the last, a forepart-trimming gage mounted on said forepart-engaging member and constructed and arranged to be removed from its gaging position without disengaging said forepart-engaging member.

15 10. A clamp for holding the forepart of a moccasin bottom against the last, a forepart-trimming gage, and pin and slot connections between the clamp and the gage whereby said gage is movable from gaging position without relaxing 20 said clamp.

11. A clamp for holding the forepart of a moccasin bottom against the last comprising a member having the general shape of the forepart of the last, a forepart-trimming gage mounted on 25 said forepart-engaging member and constructed and arranged to be removed from its gaging position without disengaging said forepart-engaging member, the trimming edge of said trimming gage in its operative position being substantially 30 parallel to the upper edge of said forepart-engaging member.

RENÉ E. DUPLESSIS.
